UNITED STATES PATENT OFFICE.

WARNER T. TABB, OF BROOKLYN, NEW YORK, ASSIGNOR TO DUPLEX ENGINE GOVERNOR COMPANY, INC., OF BROOKLYN, NEW YORK, A CORPORATION OF NEW YORK.

OPERATING GEAR.

Application filed March 18, 1920. Serial No. 367,011.

To all whom it may concern:

Be it known that I, WARNER T. TABB, a citizen of the United States, residing in Brooklyn, in the county of Kings and State 5 of New York, have invented certain new and useful Improvements in Operating Gears, of which the following is a specification.

I have invented an improved operating 10 gear; especially an operating gear designed to be used on throttle valves for internal combustion engines.

The invention disclosed herein is particularly adapted for valves to be controlled by 15 mechanism comprising an actuating magnet; and has for its object to provide means whereby said mechanism may exert its force upon the valve to move same in the exact fashion demanded by operating conditions.

20 In its preferred form, the invention embraces a resilient element located between the magnet and the valve to be actuated; and designed to transmit the force or pull of the magnet to the valve in such a manner 25 that the valve moves gradually, at a uniform rate, over its entire range of displacement between open and closed position.

Further objects and advantages of my 30 invention will appear from the following specification, in connection with the accompanying drawings; and the novel features of my valve gear are pointed out in the claims attached hereto. I do not of course, wish to limit myself to what is actually 35 shown, as I may change the construction illustrated without departing from the nature and spirit of my invention as the general meanings of the terms of the claims define same.

40 On the drawings:

Figure 1 is a top view of a complete embodiment of my invention, partly in section on the line 1—1, Figure 2;

Figure 2 is a section on the line 2—2, 45 Figure 1;

Figure 3 is an end elevation seen from the right in Figures 1 and 2;

Figure 4 is a side elevation of a casting for supporting the parts of my invention;

50 Figure 5 is an end view, from the left of what appears on Figure 4;

Figure 6 is a top view of the right half of said casting, as shown on Figure 4;

Figure 7 is a section on the line 7—7, Figure 5, of the rear part of said casting;

Figure 8 is a section on the line 8—8 of Figure 7;

Figures 9 and 10 show from the front and side one of the spring plates employed in my valve gear;

Figure 11 is a side view of a lever for moving the valve itself;

Figure 12 shows a side view of a yoke pinned to said lever;

Figures 13 and 14 are sections on lines 13—13 and 14—14 respectively, Figure 12;

Figure 15 shows one of the adjusting eccentric for the valve;

Figure 16 is a section on line 16—16, Figure 15;

Figure 17 shows how said eccentric are mounted;

Figure 18 shows one of the eccentric for adjusting the spring plates above-mentioned;

Figure 19 is a section on line 19—19, Figure 18;

Figure 20 shows the manner in which the pivot for the aforesaid lever is mounted;

Figure 21 shows how the aforesaid spring plates are mounted; and

Figure 22 is a chart illustrating the operation of the valve gear.

The same numerals identify the same parts throughout.

In the particular description of the structure which the drawings present, I employ the numeral 1 to indicate a casting having a portion 2 of relative thinness at one end with a passage 3 therethrough; and a relatively thick portion 4 at the other. In the passage 3 I locate a valve 5 and a seat 6, the valve being adapted to turn about a pivot 7 in the seat 6. Both the valve and the seat have a circular row of radially arranged openings 8; and when these openings register the valve is in its open position; and when they do not register, the valve is closed. The portion 4 supports the operating gear for the valve; which is connected to the operating gear by a flexible element or wire 9, secured to the valve in the passage 1 by being affixed

to a small hub thereon; and being led therefrom out through bearings in the sides of the portion 2, and caused to engage a pivoted rocker 10. When the rocker moves the valve 5 is of course rotated. I do not claim the valve in this application, as the same is more fully set forth and specified in the claims of my copending application for a Patent No. 367012 filed of even date herewith.

10 In practice, it is essential that the valve move gradually over its entire range from opening to closing and vice versa. It is designed to be actuated by a movable member in the form of a plunger 11 that serves 15 as an armature located adjacent one end of an electromagnet or solenoid coil 12. This magnet has a core 13 that extends into it from the opposite end, and the adjacent ends of the armature and the core are separated by a small air gap. As is well known, the force or pull exerted by a magnet increases very rapidly as the air gap between pole and armature decreases; and this fact must be taken into account in connecting the 20 valve and the armature, if a gradual and uniform movement of the valve in response to unequal variations in the effective strength or pull of the magnet is to be had.

I therefore mount on the portion 4 resilient means in the form of a leaf or bow spring 14, held at its ends, but free to bend in the middle. This spring is adapted to be flexed by the magnet, when the magnet is energized; and the spring then acts through 25 the rocker 10 to turn the valve towards closed position. When the magnet weakens or ceases to be energized, the elasticity of the spring asserts itself and the rocker is caused to return the valve to full open position. Hence the valve is actuated gradually and uniformly, as required. The mode of operation is fully illustrated with reference to the diagram in Figure 22, which will be explained fully hereinafter.

30 40 45 The ends of the spring 14 are engaged by plates 15, pivoted to the portion 4 by pins or bolts 16 and having flanges or rims 17 at their free ends in which the extremities of the spring may work. At their free ends 50 55 these plates are engaged by adjusting means or devices in the form of eccentrics 18 (Figures 18 and 19) in the portion 4, and the angularity of these plates in relation to the spring 14 by such means can be regulated; that is, the characteristics of the spring can be changed as required. These eccentrics have journals or trunnions 19 at their extremities to enable them to be pivotally mounted in the portion 4 and in the trunnions of each is a kerf 20 for a tool to enable the eccentrics to be turned as desired. Each kerf is covered by a lock washer 21 and locknut 22, arranged in counterbores in the portion 4, to secure the eccentrics in 60 65 required position. See Figure 17, which

shows similar eccentrics for another part, but mounted in the same way. Of course the manner in which the bolts 16 and the eccentrics 18 are held in the casting are matters of mechanical detail, and need not 70 be further described.

The spring 14 is preferably arranged to be flexed in a plane parallel to the valve 5, and it extends between the arms 23 of a yoke 24. This yoke carries a flexible element 25, secured by an adjustable screw 26 to the plunger 11, this spring and screw making an adjustable connection between the plunger and the yoke. Between the arms 23 is a pressure bar 27, which engages the spring 14, so that when the plunger 11 pulls on the yoke, the spring 14 is bent accordingly. The shank of the yoke 24 has the form of a pair of perforated lugs 28, pinned to a lever 29, which is joined by a link 30 to the rocker 10. This lever has a pivot in the form of a bolt 31 at one end, and carries at its other a tongue 32, located between adjusting devices or eccentrics like the eccentrics 18, and having similar kerfs, with washers and nuts to hold them in a given position. These eccentrics limit the movement of the lever, and thus fix the range of the valve 5. To make sure that the bar 27 always presses upon the spring 14, I mount an adjustable screw 33 in the base of the yoke 24, the forward end of the shank of this screw entering a recess 34 in the bar 27. A milled disk 35 on the screw 33 enables the operator to turn it easily. The eccentrics for the lever are especially illustrated in Figures 15, 16 and 17.

The mode of operation will now be clear. When the magnet is energized, the spring 14 is flexed and the yoke 24 made to pull on the lever 29 to move the rocker 10. This rocker, which is pivoted to the casting by a bolt 36, has projections 37 at its ends, and over these projections the terminal portions of the wire 8 are passed and joined by a spring 38. This wire is secured against slipping by a clamp 39, fastened to the rocker by screws; and the movement of the rocker thus produces a movement of the valve. When the magnetic pull diminishes or ceases, the valve moves back towards open position. The magnet is energized in accordance with the speed of the engine upon which the valve is placed, and when the speed approaches the predetermined limit, it acts to move the valve towards closed position and throttle the supply of motive agent. The valve 5 may be located in the fuel intake conduit of an internal combustion engine, or it may be used in the intake pipe of a steam engine, or other unit as well.

In Figure 22, I show curves A and B, indicating for the sake of example the pull of the magnet for limiting speeds of the en-

gine of 950 and 1000 revolutions respectively. From any point on either curve, the horizontal distance to the vertical axis OY gives the increase in airgap, and the distance 5 from any point on either curve to the horizontal axis OX gives the pull in pounds exerted by the magnet through such gap. Hence, the pull is greatest when the airgap is smallest. The curve C relates to the spring 10 14. The distance between any point thereon and the line OY gives the degree of movement of the plunger 11; that is, the degree of flexing of the spring; and the distance between any point on the C curve and the line 15 OX gives the pressure on the spring needed to deflect it in pounds. The spring is bent the most when the airgap is smallest and the magnet pull the strongest. The shape of the curve C approximates that of the curves A 20 and B. These curves A and B show also how much more rapidly the pull of the magnet increases as the airgap lessens. If a spiral spring or a simple bow spring were employed instead of the combination of bow 25 spring 14 and plates 15 shown in Figures 1 and 2, the shape of the curve C would be entirely different from the shape shown, and the similarity of this curve to the curves A and B would not exist; the restraining action 30 of the spring would not bear the proper relation to the motive action of the magnet in all positions of the plunger; the valve would close faster and faster as it neared its closed position; and so no gradual or 35 uniform movement of the valve would be possible. But the combination of leaf spring bearing against angularly located plates produces a restraining action which varies 40 during the movement of the plunger in the same way as the pull of the magnet varies and a gradual or uniform movement of the valve between its open and closed positions is obtained. The effect is secured whether 45 direct or alternating current to energize the magnet be employed.

The curve D shows the same characteristic as the curve C for an ordinary spiral spring. The magnet thus throttles the engine by 50 closing the valve little by little, to cut off the motive agent and check the engine as the limiting speed is approached. If this speed for any reason be exceeded, the valve would momentarily close and cut off the motive agent entirely, but would reopen the instant 55 the speed of the engine drops.

The coil 12 is provided with flanges 40 secured to the portion 4 of the casting 1 by tie bolts 41. These tie bolts engage retaining bars 42 at their outer ends, and to these 60 bars are attached bent metallic strips 43 to support the core 13. Any suitable structure of magnet that will serve the purpose may be utilized. The terminals of the coil are indicated at 44.

65 The pressure bar 27 may be loosely fitted

upon the end of the screw 33, and one end of the bar may have a recess or key-way 45 to engage a key or projection 46 in the yoke 24 to keep the bar in true transverse position with regard to the spring 14, while 70 permitting it to move towards or from the spring as the screw 33 is turned.

Having described my invention, what I believe to be new and desire to secure and protect by Letters Patent of the United 75 States is:—

1. The combination of a magnet, a valve to be actuated by the magnet, and resilient means between the magnet and the valve designed to enable the magnet to actuate 80 the valve gradually and uniformly in response to unequal variations in the force exerted by the magnet.

2. The combination of a magnet, an armature therefor, a yoke connected to the armature, a valve, and a bow spring between 85 said valve and said yoke.

3. The combination of a magnet, a valve to be actuated by the magnet, resilient means 90 between the magnet and the valve designed to enable the magnet to actuate the valve gradually and uniformly in response to unequal variations in the force exerted by the magnet, and means for adjusting said resilient means. 95

4. The combination of a magnet, an armature for same, a yoke connected to the armature, a valve, a bow spring between 100 the valve and the yoke, and means for adjusting said spring.

5. Operating gear comprising a bow spring, a pair of pivoted plates, each of which engages said spring adjacent the ends thereof, and adjusting devices to regulate the pressure of said plates on said spring. 105

6. Operating gear comprising a yoke, a movable member, an adjustable connection between said yoke and said member, a lever pinned to the shank of said yoke, a rocker linked to the lever, and a bow spring between the arms of said yoke and normally opposing the movement of same. 110

7. The combination of a yoke, a pressure bar extending between the arms thereof, and a bow spring held at its opposite ends and being engaged by said bar intermediate said ends. 115

8. The combination of a yoke, a bow spring held at its opposite ends, a bar carried by the arms of said yoke to engage said spring between said ends, and adjusting devices for the ends of the spring. 120

9. The combination of a yoke, a movable member adjustably connected to the yoke to move same, and a bow spring between the arms of the yoke to oppose the movement thereof. 125

10. The combination of a yoke, a movable member connected to the yoke to move same, a lever pinned to the shank of the yoke, and 130

adjustable devices to limit the movement of the lever.

11. A yoke, a movable member to operate same, a bow spring between the arms of the yoke, said spring being held against movement at its ends, a pressure bar between the ends of the yoke to engage the spring, and an adjusting screw to control

said bar and mounted in the base of said yoke.

In witness whereof, I have signed my name to this specification this 2nd day of March 1920.

10

WARNER T. TABB.

Witness:

H. A. ROBERTS.
